UNITED STATES PATENT OFFICE

HARVEY J. LOUNSBURY, OF GLEN ELLYN, ILLINOIS, ASSIGNOR TO W. H. MINER, INC.,
OF CHICAGO, ILLINOIS, A CORPORATION OF DELAWARE

DOOR CONSTRUCTION

Application filed October 10, 1928. Serial No. 311,521.

This invention relates to improvements in door construction. One object of the invention is to provide an improved construction of double doors of the hinged type, especially adapted for railway cars, wherein the meeting edges of the doors are reinforced to provide rigidity and strength, and means is also provided on each door overlapping the edge section 5 of the adjacent door at the meeting edges of the doors to provide combined stop means and a weather and spark seal.

A further object of the invention is to provide a double door construction for railway 15 box cars, especially adapted for use at the end of the car and forming the car end wall, wherein the meeting edges of the doors are reinforced and rigidified by vertically disposed H-beam sections having the webs there- 20 of arranged parallel to the longitudinal center line of the car, and wherein the meeting edges of the doors are provided with combined stop and sealing strips, one of said strips being secured to the inner face of the 25 H-beam of the door first to be closed and overlapping the inner flange of the H-beam of the other door, and the other of said strips being secured to the outer flange of the H-beam of the door last closed and overlapping 30 the outer surface of the H-beam of the first named door.

Other and further objects of the invention will more clearly appear from the description and claims hereinafter following.

35 In the drawings, forming a part of this specification, Figure 1 is an end elevational view of a car, showing a double door construction and illustrating my improvements in connection therewith. Figure 2 is a horizontal, sectional view, corresponding substantially to the line 2-2 of Figure 1. Figure 3 is a transverse, vertical, sectional view, corresponding substantially to the line 3-3 40 of Figure 2, the door locking mechanism and the buffer block of the car being omitted for the sake of clearance. And Figure 4 is an enlarged, horizontal, sectional view through the inner end portion of the door 45 shown at the left in Figure 2, the filler block

being omitted to more clearly illustrate certain details of the invention.

In said drawings, the body of the car is designated by the character 10—the car illustrated is of that type of box car provided with end doors, which especially adapts the same for use in connection with automobiles. The end sill of the car is designated by 11 and has the striking casting 12 secured thereto. In the illustration in Figure 1, the unessential parts of the car are omitted, that is, the railway car truck and the associated parts are not shown. The roof of the car is designated by 13 and is provided with the usual running board 14. The door frame structure is defined by a top member 15 in the form of a transverse beam, a threshold 16 and the usual side members of the door frame which in this case are the side walls of the car. The two hinged doors of the car are 55 designated respectively by 20 and 21 and are supported from the side walls by a plurality of hinges 22-22. The doors 20 and 21 are provided with the usual operating mechanism comprising the members 23-23 and 60 associated parts, and also with a locking means 24.

The operating members 23-23 comprise rotary shafts mounted on each door having crank arms at the top and bottom ends thereof of cooperating with keeper means secured to the top and bottom members of the door frame. The operating members 23 are employed to force the doors tightly closed and also to facilitate the opening of the same. 65 The locking means comprises reciprocating bars operated by handle means, the bars engaging locking keepers secured respectively to the top member of the door frame and the striking casting 12.

In carrying out my invention, I provide the doors 20 and 21 with overlapping combined stop and sealing strip means at their meeting edges, and also reinforcing means along said edges, as more clearly hereinafter pointed out. The two doors 20 and 21 are of similar design, each comprising a pair of vertical frame members 25-25 at the inner and outer edges thereof, and top and bottom frame members 26-26 secured to said side mem- 70 75 80 85 90 95 100

bers. The main body portion of each door comprises a corrugated sheet metal panel 27 which is suitably secured to the frame members 25—25 and 26—26. The top and bottom frame members 26 are housed within channel beam members 28—28. Each channel beam member comprises a web section 29 which is disposed substantially horizontally and the top beam member 28 is provided with a pair 10 of spaced depending side flanges 30—30 while the bottom beam member 28 is provided with spaced upstanding flanges 31—31. The flanges 30 and 31 at the outer side of each door are secured to the sheet metal panel member 27 of said door, the same being preferably riveted thereto. On the inner side each door is provided with the usual panel member 32 which is fixed to the frame members 25—25 and 26—26.

20 The meeting edges of the doors 20 and 21 are suitably reinforced by vertically disposed H-beams 34—34. The H-beam 34 of each door has the web thereof disposed in a plane substantially at right angles to the plane of the door, and the flange sections 35—35 thereof disposed in planes parallel to the plane of the door. As most clearly illustrated in Figures 2 and 4, the transverse flange section 35 of the H-beam is secured to the top and bottom beams 28 by means of rivets 36 or any other suitable securing means which extends through the flanges 30 and 31 of the beams 28. Each H-beam is also fixed to the corresponding door member by having the web 35 thereof secured to the sheet metal panel member 27, the sheet metal panel member 27 having the inner edge section thereof turned inwardly, as indicated at 37, and riveted to the web member of the H-beam, as most clearly shown in Figures 2 and 4. It will be evident that each H-beam is thus rigidly secured to the inner edge of the door and forms a rigidifying and strengthening member for said edge. •

45 The combined stop, weather and sealing strip means of each door comprises a sheet metal section secured to the edge of the same and overlapping a portion of the inner edge of the adjacent door. As most clearly shown 50 in Figure 2, the door 20 is provided with a vertically disposed strip 38 secured to the flange section 35 of the H-beam of said door. The strip 38 is of such a length as to overlap the inner face of the flange section 35 of the 55 H-beam secured to the door 21 when the doors are closed.

As shown in Figure 2, the section of the strip 38 engages in back of the H-beam of the door 21 and is offset with respect to the remaining portion of said strip so that the doors will be in transverse alinement when closed. The strip 38 may be secured to the flange 35 of the H-beam of the door 20 in any suitable manner and is herein shown as riveted thereto, the strip being disposed on the inner side

of said flange, thereby providing a more rigid connection between the strip and the H-beam.

The H-beam of the door 21 has a similar combined stop and sealing strip 38 secured to the outer flange 35 of the H-beam thereof, the strip being riveted to the inner face of the flange 35 of said H-beam and having the free edge section thereof offset so as to overlap and engage with the outer face of the outer flange section 35 of the H-beam of the door 20.

70 In operating the doors, the one indicated by 20 is first closed by means of the operating mechanism 23 of said door. With this door in the closed position, the door 21 is swung inwardly and, as will be evident, the flange section 35 at the inner side of said door will clear the outer flange section 35 of the H-beam of the door 20. Inward swinging movement of the door 21 will finally be limited by engagement of the inner flange section 35 of the H-beam with the stop strip 38 secured to the inner side of the door 20 and by engagement of the stop strip 38 on the outer side of the door 21 with the outer face of the flange section 35 of the H-beam of the door 20.

75 As will be evident, the stop strips 38 which cooperate with the H-beams form a positive limiting means to determine the closed position of the doors and hold the same in transverse alinement. It will be understood that 95 the door 21 is forced to its closed position by the operating means 23 thereof in the usual manner. After the doors have been closed, the same are tightly locked by the locking mechanism 24.

80 The reinforcing H-beams at the meeting edges of the doors of my improved construction form an effective rigidifying and strengthening means to prevent bulging of the doors due to outward pressure exerted thereon, and my improved sealing strip means, comprising the inner and outer combined sealing strip and stop members, in addition to forming positive stop means, also forms an effective double weather and spark 100 seal.

85 While I have herein shown and described what I consider the preferred manner of carrying out my invention, the same is merely 115 illustrative and I contemplate all changes and modifications which come within the scope of the claims appended hereto.

I claim:

1. In a door for railway cars, the combination with top and bottom channel-shaped beam members; of a beam of H-shape cross section forming one of the side edges of the door, the web of said H-beam being disposed at right angles to the plane of the door, one of the flanges of each of said channel beams 125 at the same side of the door being secured to the flange of the H-beam at the corresponding side of the door; and sheet metal panel means forming the main body portion of the door, the top and bottom edges of said panel being 130

secured to the remaining flanges of said channel members, and the edge section of said sheet metal panel means at said H-beam being turned inwardly at an angle to the main body 5 of the panel and secured to the web of the H-beam.

2. A door construction for railway cars including: a pair of doors hinged at their outer edges, the inner edge of each door being reinforced by a vertically disposed H-beam having the web thereof disposed at right angles to the plane of the door and the flanges thereof disposed in planes parallel to the plane of said door, said H-beam being fixed to the door 10 proper, the H-beam of each door having a combined stop and sealing strip secured thereto, said sealing strips being disposed respectively on the inner and outer sides of the doors, the strip of each door being secured to 15 the inner face of the flange of the H-beam at the corresponding side of the door and having an offset portion overlapping the outer face of the flange at the same side of the other door.

20 25 In witness that I claim the foregoing I have hereunto subscribed my name this 8th day of October, 1928.

HARVEY J. LOUNSBURY.
